UNITED STATES PATENT OFFICE.

FREDERIC E. BALDWIN, OF NEW YORK, N. Y.

ACETYLENE-LAMP.

1,083,427.

Specification of Letters Patent.

Patented Jan. 6, 1914.

Application filed September 12, 1913. Serial No. 789,421.

To all whom it may concern:

Be it known that I, FREDERIC E. BALDWIN, a citizen of the United States, residing at New York, county of Richmond, 5 and State of New York, have invented certain new and useful Improvements in Acetylene-Lamps, fully described and represented in the following specification and the accompanying drawings, forming a 10 part of the same.

This invention relates to improvements in acetylene lamps and particularly miners' acetylene lamps. In lamps of this class, it is common to provide a reflecting device 15 back of the burner and, owing to the rough conditions under which such lamps are used, such reflectors are subjected to blows which bend and distort them. Furthermore, it sometimes happens that when a 20 sudden increase of air pressure is caused in a mine, as for example at the time of a blast, such increased pressure tends to prevent the outward flow of acetylene to the burner, so that the flame is extinguished, 25 thus necessitating the relighting of the lamp.

The principal object of this invention is to provide a reflector mounting and a bracing device therefor whereby the reflector 30 will be held against distortion by ordinary blows and at the same time a simple and light construction is permitted.

A further object is to combine with such reflector bracing device means for preventing the flame from being extinguished by 35 sudden increases in air pressure in the mine.

With these general objects in view, the invention consists in the features, details of construction and combination of parts 40 which will first be fully described and then particularly pointed out.

In the drawings illustrating the best embodiment of the invention,—Figure 1 is an elevation, partly in section, of a lamp embodying the present invention. Fig. 2 is 45 a front elevation, partly broken away, of the same lamp. Fig. 3 is a horizontal sectional view on the line 3—3, Fig. 1.

Referring to the drawings, 1 is the upper 50 part of the lamp and 2 the lower part, these two parts being united in any suitable way, as for example by screw threads as shown, a gasket or packing ring 4 being inserted between two flanged portions of the two parts. The upper part 1 is provided with 55 a diaphragm 5 and has a closed top 6 pro-

vided with a tubulature 7 and closed by a head or cap 8, usually provided with an air-hole. To the diaphragm 5 and depending therefrom is secured a water supply pipe 9 terminating a short distance above the bottom of the lamp. Through the top 6 of the lamp and through the water supply pipe 9 extends a poking-rod 10, whose outer end is bent at an angle to serve as a 60 handle. The rod 10 does not fit tightly in the water supply pipe 9, but is so proportioned as to provide a small annular space around said rod 10 so as to permit the desired feed of water from above the partition 5 to the lower part of the lamp. The space above the partition 5 serves as a water-chamber and the space in the bottom of the lamp serves as a generator-chamber in which is placed carbid. 65

The upper part of the lamp is provided with a burner tube 11, just below the partition 5, this burner tube extending outward in a radial direction as shown in Fig. 1. Against its inner end is placed a body of 70 porous material serving as a filter, this porous material usually consisting of a piece of felt, or the like, as indicated at 12, Figs. 1 and 3. The felt is held in place between the inner end of the burner tube 11 and the 75 water supply pipe 9 by its own elasticity. The burner tube is provided outside the lamp casing with a reflector 13 removably secured to the burner tube in any suitable way, as for example by a screw thread connection shown in Fig. 1. At the extreme 80 outer end of the burner tube is mounted a burner 14, which fits tightly on the end of the burner tube and is held frictionally thereto. The burner has a flanged rim which engages the reflector 13 near the center of 85 the same. 90

In the best embodiment of the invention, the burner tube is constructed of such a length as to provide an appreciable space 95 between the back of the reflector 13 and the adjacent outer wall of the lamp casing. Between the reflector and the casing is located a reflector bracing device or support of such suitable construction and arrangement 100 as to engage the back of the reflector at a plurality of points remote from the burner tube, this bracing device bearing against the lamp casing so that any strains due to 105 blows will be transmitted to the casing, thereby bracing the reflector against distortion. In the present embodiment of the in- 110

vention, this reflector bracing device is made in the form of a circular boxing, shown in the drawing as somewhat trumpet-shaped, the bottom of said boxing being so shaped as to fit against the lamp casing. This boxing is indicated at 15 and, in the present example, is provided with inward turned flanged outer edges which bear against the back of the reflector at such a distance from its axis and from the burner tube as to give a good support to the reflector.

The interior of the boxing, in the best embodiment of the invention, is in communication with the outer air through suitable openings, as for example the openings 16 in the reflector around the burner tube and openings 17 in the periphery of the boxing as shown in Figs. 1 and 3. The boxing is put in place by slipping it over the burner tube, whereupon the reflector may be screwed onto the burner tube and as it comes in contact with the outer face of the boxing, it will clamp the same and bring it to a central position, that is to say, a position coaxial with the burner tube. Furthermore, owing to the resiliency of the flanged outer edges of the boxing, the latter will accommodate themselves to the back of the reflector so as to provide a uniform support, notwithstanding any slight variations in manufacture. The burner is then slipped over the projecting end of the burner tube where it is held by friction. By unscrewing the reflector, the burner will be forced off the end of the burner tube and upon removal of the reflector the boxing 15 may be removed if desired. This boxing is a convenient receptacle for spare burners.

In that embodiment of the invention comprising all the advantageous features, the boxing is arranged to contain a suitable pressure controlling means comprising a reservoir for gas, arranged to have its capacity varied by changes of atmospheric pressure. In the present example, this reservoir consists of a bag 18 of elastic material such as rubber, located within the boxing 15 and having its interior in communication with the interior of the burner tube and advantageously just back of the burner. In the present example, I have illustrated this controlling means as an annular bag surrounding the burner tube. The bag 18 is provided with a tubing 19 of elastic material such as rubber, which connects with the tube 20 projecting from the burner tube and having its free end bent over in order to permit the quick and convenient attachment and removal of the bag 18. In order to strengthen the tube 20, it may be soldered or otherwise attached to the front of the lamp casing. The boxing 15 is provided with a suitable opening, through which the tubing 19 of the bag 18 may extend.

It will be observed that when water is fed

from the water-chamber to the generating-chamber in the well known manner, the acetylene gas thereby generated will pass through the porous material 12 to and through the burner tube 11 and may be lighted at the burner 14. If, now, a sudden increase in the atmospheric pressure outside the lamp should take place, any tendency of this pressure to drive back the outflowing gas in the burner tube 11 will be overcome by the compression of the elastic bag 18, which will result in an equally sudden increase of pressure within the burner tube just back of the burner, thus balancing the pressure inside said burner tube with the pressure of the air outside the lamp. Upon a fall of pressure outside, the bag 18 will again expand to its normal dimensions. By means of the flexible connection 19 between the tube 20 and the bag 18, the further advantage is attained that in case a leak should occur in said bag and gas from the generating-chamber escape from this leak and ignite, the flame may be immediately extinguished by compressing the elastic tube 19, as with the fingers. When the lamp is used under conditions where the sudden increase in pressure is not to be feared, the bag 18 may readily be removed and the end of the tube 20 plugged in any suitable way. Under these conditions, the boxing 15 becomes a convenient place in which to carry extra burners.

It will be noted that the bag 18 constitutes a means for varying the pressure within the burner tube, in response to the variations of the atmospheric pressure to which the burner is exposed. Since the inner end of the tube 20 is very close to the burner, any increase in pressure upon the bag 18 will produce an immediate corresponding increase of pressure at the inner end of the burner, thus at once counteracting any tendency to put out the light. This result could not be satisfactorily accomplished if the counteracting pressure were compelled to travel any appreciable distance before reaching the inner end of the burner.

What is claimed is:—

1. The combination, with a lamp casing arranged to furnish a supply of gas, and a burner tube projecting therefrom, of a reflector carried by and detachable from the burner tube, and a reflector support mounted between the lamp casing and the back of the reflector and clamped in place by said reflector.

2. The combination, with a lamp casing, a burner tube projecting therefrom, and a reflector carried by the burner tube, of a support surrounding the burner tube, said support having its rear face engaging the lamp casing and its front arranged to support the reflector at a distance from the burner tube.

3. The combination, with a lamp casing, a burner tube projecting therefrom, and a reflector carried by the burner tube at a point away from said casing, of a support 30
5 rounding the burner tube and having its rear face engaging the lamp casing, said support having an open front end arranged to engage the back of the reflector at a plurality of points remote from the burner tube.
- 10 4. The combination, with a lamp casing, a burner tube projecting therefrom, a reflector held to the burner tube by screw threads, and a burner on the end of the burner tube beyond the reflector, of a substantially cylindrical support surrounding the burner tube and having its rear end shaped to fit the lamp casing, the front end of said support being arranged to contact with the back face of the reflector, substantially in a circle concentric with the burner tube. 40
- 15 5. In an acetylene lamp, the combination, with a casing containing a gas-supply chamber, a burner tube leading from said gas-45
20 supply chamber, and a burner outside the lamp and carried by said burner tube, of a pressure controlling device located outside the lamp casing and having its interior in communication with the interior of the burner tube back of the burner.
- 25 6. In an acetylene lamp, the combination, with a lamp casing containing a gas-supply chamber, a burner tube leading therefrom, a burner outside the casing and carried by the burner tube, and a reflector carried by the burner tube at a point away from said casing, of a reflector support surrounding the burner tube and having its rear face engaging the lamp casing and its front arranged to support the reflector away from the burner tube, and a pressure controlling device located within said support and having its interior in communication with the interior of the burner tube back of the burner.

In testimony whereof, I have hereunto set my hand, in the presence of two subscribing witnesses.

FREDERIC E. BALDWIN.
